(57) **CLAIM**

The ornamental design for a clip, as shown and described.

DESCRIPTION

FIG. 1 is a perspective view of a clip showing our new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The dash-dot-dash broken lines immediately adjacent the shaded areas represent the bounds of the claimed design. The dash-dot lines depict portions of the clip that form no part of the claimed design.

1 Claim, 7 Drawing Sheets
